UNITED STATES PATENT OFFICE

150,431

DESIGN FOR A FISH LURE

John S. Kuslich, St. Paul, Minn.

Application October 4, 1946, Serial No. 133,743

Term of patent 7 years

(CL. D31—4)

To all whom it may concern:

Be it known that I, John S. Kuslich, a citizen of the United States, residing at St. Paul, in the county of Ramsey and State of Minnesota, have invented a new, original, and ornamental Design for a Fish Lure, of which the following is a specification, reference being had to the accompanying drawing, forming a part thereof.

Except for the metal elements the drawing is lined to indicate the colors red and green.

Figure 1 is a top plan view of a fish lure showing my new design.

Figure 2 is a side elevation thereof showing in dotted line the relative position of a fish hook attached thereto.

Figure 3 is a bottom plan view of the fish lure shown in Figures 1 and 2.

The essential features of my design reside in the portion shown in full lines.

I claim:

The ornamental design for a fish lure, as shown and described.

JOHN S. KUSLICH.
